Primary Examiner — Ricky Pham(74) *Attorney, Agent, or Firm* — Rumit Ranjit Kanakia(57) **CLAIM**

The ornamental design for a chef knife, as shown and described.

DESCRIPTION

FIG. 1 is a front elevational view of a chef knife showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof; and,

FIG. 7 is a perspective view of a chef knife showing my new design.

The broken lines in the figures are for the purposes of illustrating portions of the chef knife, which form no part of the claimed design.
